RECORD MATERIAL EQUIPMENT FOR CASH REGISTERS

Joseph J. Klosterman, deceased, late of Dayton, Ohio, by Mary Klosterman, executrix, Dayton, Ohio, assignor to The National Cash Register Company, Dayton, Ohio, a corporation of Maryland

Original application February 10, 1942, Serial No. 430,214. Divided and this application March 15, 1946, Serial No. 654,645

16 Claims. (Cl. 197—133)

1

This present invention relates to combined cash registers and adding machines, and is particularly directed to improvements in the type of machine disclosed in United States Letters Patent No. 2,286,116, issued June 9, 1942, to B. M. Shipley, and is a division of the United States application for Letters Patent of E. J. Carey, Frederick Gantner, J. J. Klosterman, deceased, and J. B. Geers, deceased, Serial Number 430,214, filed February 10, 1942, which application has matured into United States Letters Patent No. 2,443,652 dated June 22, 1948.

One object of this invention is to provide novel printing mechanism and controls therefor.

A further object is to provide novel record material supporting means for moving the record material from reading position to printing position and return, and for feeding said record material, said record material supporting means being readily removable from the machine for adjustment and for the convenient removal and insertion of the record material.

A further object is to supply novel means to press the record material against the printing wheels to secure a permanent record of each transaction.

With these and incidental objects in view, the invention includes certain novel features of construction and combinations of parts, the essential elements of which are set forth in appended claims, and a preferred form or embodiment of which is hereinafter described with reference to the drawings which accompany and form a part of this specification.

In said drawings:

Fig. 1 is an end view, as observed from the right of the machine, of the removable framework for supporting the record material.

Fig. 2 is a righthand end view of a portion of the rockable record material framework, showing said framework and the mechanism supported thereby in normal or reading position.

Fig. 3 is a righthand view of the mechanism of Fig. 2 after it has been moved from normal position to working or printing position.

Fig. 4 is a detail of the cam and part of the pitman for moving the impression means and the record material frame from reading position into printing position.

Fig. 5 is a facsimile of a fragmentary portion 50 cash and charge items cannot be printed in the

2

of the multiple column record material used in the machine, and illustrates one method of using the machine as a regular business machine or cash register.

Fig. 6 is a front elevation of the removable record material supporting framework.

Fig. 7 is a side-spacing view of the mechanism for supporting the lefthand end of the record material receiving roll, and the ratchet mechanism for manually advancing said receiving roll.

Fig. 8 is a detail view, as observed from the right of the machine, showing a portion of the mechanism for moving the record material from reading position to printing position, and for 15 automatically advancing or line-spacing the record material.

Fig. 9 is a detail view of the mechanism for manually rotating the record material receiving roll to advance the record material.

Fig. 10 is a fragmentary plan view of a portion 20 of the receiving roll for the record material and the mechanism for rotating said receiving roll to line-space the record material.

Fig. 11 is a detail view of a portion of the 25 mechanism shown in Fig. 10 for automatically rotating the receiving roll for the record material.

GENERAL DESCRIPTION

As previously stated, this divisional application 30 is directed particularly to the record material, the mounting and control thereof, and also the impression means and its control, adapted for use in a cash register or adding machine.

The record material, a fragmentary portion of 35 which is shown in Fig. 5, is comparatively wide, and is divided into nine vertical columns, the extreme lefthand column of which is considerably larger than the other eight columns, and is used for the printing of the ledger numbers and all other identifying data, as well as amounts. In addition, the lefthand column is used for the autographic entering of identifying data opposite the printed entries.

Likewise all totals and sub-totals are printed 40 in this wide lefthand column and when the machine is used as an adding machine, it is possible to print any amount desired in this lefthand column.

When the machine is used as a cash register, 45 cash and charge items cannot be printed in the

lefthand column, and therefore must be printed in one of the other eight columnar divisions located to the right thereof. Also, when the machine is used as a cash register, the received-on-account and paid-out items may be printed in the lefthand column, or in any other desired one of the eight columns of the record material. However, no-sale items are invariably printed in the lefthand column.

The web of the record material is contained on a supply roll and is unwound therefrom and threaded around various guide rods, between the impression mechanism and the printing mechanism, and thence onto a receiving roll. The entire record material mechanism, including the supply roll, the receiving roll, guiding means therefor, and the impression platen, is mounted in a framework which is rockable from a normal or reading position and return, to move the record material to and from printing position without the necessity of sliding the web of record material over stationary guides and supports. When the record material is in reading position, the last few entries thereon are visible through an opening in the closure of the cabinet, which closure gives access to the record material mechanism. Likewise, the autographic portion of the record material is accessible through said opening for the autographic entry of descriptive data thereon.

The rockable framework which supports the record material is in turn supported by a framework, which is removably mounted in the front of the machine and which is accessible through the closure above mentioned. The closure, which gives access to the record material mechanism, is not only locked in closed position, but is automatically unlocked when a total control slide (not shown in this divisional application) is moved to either Read total position or Add and Reset position. When the closure is open the removable framework may be easily removed from the machine, and as this framework carries the rockable framework, the entire record material assembly, including the supply roll and the receiving roll, may be quickly and conveniently removed from the machine for the changing of record material, or for the making of adjustments to the record material mechanism.

As the record material framework is rocked from reading position to printing position, a portion of the guiding means for the web of the record material is momentarily retracted, to release the tension on the web of said record material, and while the tension is thus released the automatic means for rotating the record material receiving roll functions to line-space the record material. A key located on the lefthand side of the keyboard is provided for actuating mechanism which rotates the record material receiving roll for manually advancing or line-spacing said record material.

DETAILED DESCRIPTION

Machine framework and operating mechanism

The mechanism of the machine is supported by two main frames 60 and 61 (Figs. 1 and 6) secured to a base which is not shown in this divisional application. All of the mechanism of the machine is also enclosed in a suitable cabinet 69, a portion of which is shown in Fig. 1.

A conventional type of electric motor (not shown herein) drives a main shaft 130 (Fig. 3) one clockwise revolution for each operation of the machine.

Type wheels

Type wheels 319 for the four lower order amount banks are supported in a shiftable framework which is positioned under the influence of column selecting keys to select the different columns of the record material (Fig. 5) for the entering of various items.

10 There is only one type wheel 319 shown in this divisional application. The mechanism for differentially positioning the type wheels 319 and the shiftable framework for shifting the type wheels is not shown in this divisional application, but is fully illustrated in the parent application, Serial Number 430,214.

Record material mechanism

20 The supply and receiving rolls for the record material, shown in Fig. 5, are supported in a framework which is removably supported between the main frames of the machine, and which is located at the front of the machine where it is accessible through a closure in the cabinet portion of the machine.

25 The closure giving access to the record material is locked in closed position when the total control slide (shown and described in the parent application, Serial Number 430,214) is moved to either the Read total position or the Add and Reset position. Therefore, the record material is accessible only to those having keys to a lock in the total control slide, which lock is used for locking the slide in either Register position or Lock-register position.

30 The last few items entered on the record material are visible through an opening in the top part of the closure giving access to the record material, said opening being covered with a transparent material such as glass or pyralin. The extreme lefthand portion of the record material is reserved for the autographic entering of various data, and an opening in said transparent material gives access to this portion of said record material for this purpose.

35 Referring now particularly to Figs. 1, 2, 3, 6, and 9, the removable framework for supporting the record material supply and receiving rolls comprises a right plate 726 and a left plate 727 connected in fixed relationship to each other by a rod 728. Trunnions formed by opposite ends of the rod 728 engage curved slots 729 in each of two similar plates 730 and 731 secured, respectively, to the right side frame 61 and to the left side frame 60. Similar extending legs of the plates 726 and 727 have identical inverted V-shaped notches 732 and 733 adapted to engage, respectively, the circumference of similar hubs secured in axial alignment with each other in the frames 60 and 61, said hubs providing bearing supports for a shaft 134. The rod 728, in cooperation with the curved slots 729, forms a hinged support for the record material framework, and when said framework is in operating position, as shown in Fig. 1, the V-shaped notches 732 and 733 engage the hubs in the frames 60 and 61, as here shown, to properly locate said framework in operating position. Two similar latches 735 (Figs. 1 and 6) pivoted on studs 736 in plates 726 and 727, are urged clockwise by springs 737 into engagement with stationary studs 738 in the frames 60 and 61, to latch the record material framework in operating position, as here shown.

40 To remove the record material framework from the machine or to swing said framework to a

45

more accessible position for the removal of the printed portion of the record material wound on the receiving roll, bent-over finger-pieces 739 on the two latches 735 are grasped, and said latches are rocked counterclockwise, as viewed in Fig. 1, against the action of the springs 731, out of engagement with their respective studs 738, after which the entire record material framework may be rocked outwardly or counterclockwise, the rod 728 and the slots 729 forming a pivot for said framework until similar projections 741 on downward extensions of the plates 726 and 727 come into contact with the studs 738 to terminate rocking movement of said framework and to hold said framework in an accessible position. If it is desired to remove the framework from the machine, the rod 728 may be lifted out of the open upward ends of the slots 729.

A supply roll 742 (Figs. 2, 3, 6, and 8) is rotatably supported by a framework comprising end plates 743 and 744 maintained in spaced relationship to each other by a rod 745 and a shaft 746, both freely engaged by said plates. The framework for supporting the supply roll 742 is rotatably mounted between the plates 726 and 727 by means of two axially aligned trunnion studs 747 in each of the plates 743 and 744 in cooperation with hubs 748 in said plates 726 and 727. The web of the supply roll 742 is wound around a metal tube or core 749 (Figs. 6 and 8), the inside circumference of one end of said core 749 fitting over a tenon of an axle 750 journaled in a bushing in the plate 744, and the inside circumference of the other end of said core 749 fitting over a similar tenon on a spring-pushed plunger 751, rotatably mounted in a bushing in the plate 743, said plunger 751 being in axial alinement with said axle 750.

To mount the supply roll 742 in the framework 743 and 744, the righthand end of the core 749, as viewed in Fig. 6, is slipped over the tenon of the spring-pushed plunger 751, and said plunger is pushed to the right against the action of its spring until the lefthand end of the core may be slipped over the tenon on the axle 750. Each of the plates 726 and 727 (Figs. 1, 2, 6 and 9) has an identical camming slot 752, which slots are engaged by similar rollers 753 on two similar levers 754, rotatably supported on opposite ends of the rod 745. Rearwardly extending arms of the levers 754 support a rod 755, said rod in turn being pivotally connected by two similar links 756 (see also Fig. 8) to receiving roll support arms 757 and 758 secured in fixed relationship to each other on the shaft 746.

By referring to Figs. 6 and 8 it will be seen that the web of the record material is unwound from the supply roll 742 and threaded around the rods 745 and 755 and a rod 759 supported by the arms 757 and 758, thence onto a core 760 for a record material receiving roll 761. The core 760 is similar in every respect to the core 749 for the supply roll, and is rotatably supported between the arms 757 and 758.

The righthand end of the receiving roll core 760 has therein two diametrically opposed clutch cuts adapted to engage two diametrically opposed tenons on a clutch 762 (Fig. 10) secured on the end of a plunger-like axle 763, rotatably supported in a bushing 764, secured in the arm 757. Also secured to the axle 763 is a knurled finger wheel 765 having therein a slot which engages an angular tongue 766 on a disk 767 secured to one end of a hub 768 rotatably mounted on the axle 763. The hub 768 has secured on the other end thereof

a disk 769 and a receiving roll feed ratchet 770. A feed pawl 771 (Figs. 6, 10 and 11) pivoted on a stud 772 carried by a paper feed disk 773, free on the axle 763, is urged into engagement with the teeth of the ratchet 770 by a spring 774. Likewise a ratchet retaining pawl 775, free on a stud 776 in the arm 757, is urged clockwise (Fig. 11) into engagement with the ratchet by a torsion spring 777. The disk 773 carries a stud 780 pivotally supporting the lower end of a link 781 (Fig. 8), the upper end of which has a slot 782, which embraces the tenon of a stud 783 in a lever 784, free on the rod 745. The lever 784 has therein a hole which freely engages a tenon of a stud 785 secured in the lever 754 (Fig. 2).

Inasmuch as the record material feeding means is operated in conjunction with the impression means, the manner in which the lever 754 operates the record material feeding mechanism, described above, will be explained presently in connection with the description of said impression means.

The lefthand end of the core 760 for the receiving roll 761 (Figs. 6, 7 and 8) is supported by a pilot washer 786 which engages the inside circumference of said core, said washer 786 being riveted to the face of a spring-pushed plunger 787 having two diametrically opposed tenons adapted to engage two diametrically opposed clutch cuts in the lefthand end of the core 760. The tenons on the plunger 787 engage corresponding notches in the large diameter of a counterboring in a ratchet 789 to form an operating connection between these two parts. The small diameter of the counterboring in the ratchet 789 rotatably mounts said ratchet on a fixed stud in the arm 758. A hub portion of the ratchet 789 has therein an annular groove which is engaged by a retaining clip 790 (Fig. 7) secured to the arm 758 to hold the ratchet and connected parts against lateral displacement.

A ratchet operating pawl 791 (Fig. 9) has a slot 792 which fits loosely over the rod 759, and a torsion spring 793 urges said pawl 791 clockwise and rearwardly to normally maintain a tooth on the forward end thereof in contact with the teeth of the ratchet 789.

A disk 788, secured to the face of the ratchet 789, and the face of the finger wheel 765 (Figs. 7 and 10) form flanges for guiding the web of the record material around the core 760. Said disk 788 also serves to maintain the tooth of the pawl 791 in lateral alinement with said ratchet 789.

When the record material framework is in normal or reading position, as shown in Fig. 9, a rounded surface 794 on the pawl 791 is in operating relationship with a stud 795 in a lever 796 pivoted on the shaft 734. A boring in the lever 796 is freely engaged by a tenon of a stud 797 in the lower end of a link 798, the upper end of which link is pivotally connected to one arm of a lever 799, free on the shaft 212. A stud 800 in another arm of the lever 799 engages a slot in the stem of the record material space key 195, said key having parallel slots therein which engage studs 801 and 802, secured to the left frame 60. A spring 803 urges the key 195 upwardly to normally maintain said key and connected parts in normal position, as shown in Fig. 9.

Depression of the key 195, when the record material framework is in normal position, as shown in Fig. 9, rocks the lever 799 clockwise, which through the link 798 rocks the lever 796 counterclockwise, causing the stud 795 in con-

operation with the surface 794 to shift the pawl 791 forwardly against the action of the spring 793 to rotate the ratchet 789 and the core 760 one tooth-space to line-space the record material. A retaining pawl 804 free on a stud in the arm 758 is urged counter-clockwise by a torsion spring 779 to normally maintain the tooth of said pawl in engagement with the teeth of the ratchet 789 to prevent retrograde movement of the ratchet and the record material receiving roll 761.

In applying the receiving roll core 760 the righthand end thereof, as viewed in Fig. 6, is slipped over a pilot washer 778 (Fig. 10) secured to the face of the clutch 762, after which said clutch, the wheel 765 and the axle 763 are depressed against the action of their spring until the lefthand of the core 760 may be slipped over the pilot washer 786 (Fig. 7). The washer 786, together with its plunger 787, is forced inwardly into engagement with the core 760 by a compressible spring in the counterboring in the ratchet 789. After the core 760 has thus been mounted in the printer framework, the knurled finger wheel 765 (Fig. 10) is rotated manually until the tenons of the clutch 762 and the plunger 787 drop into their corresponding clutch cuts in opposite ends of the core 760 to operatively connect said core to the automatic line-spacing mechanism and to the hand line-spacing mechanism.

After the core 760 is thus mounted in the record material framework the web of the record material is unwound from the supply roll 742 (Figs. 8 and 9) and threaded around the rods 745, 755 and 759, after which the end of the web is inserted in a slot in the core 760 and said core is revolved manually by the finger wheel 765 to start the record material winding around said core 760.

Impression mechanism

The impression mechanism for printing in any of the columns of the multi-column record material shown in Fig. 5, comprises a platen which extends across the width of all printing columns of the record material, said platen being operated by a toggle arrangement which causes a squeeze type of impression to be effected rather than the conventional hammer-blown type of impression. The impression mechanism is supported by the framework 743 and 744 which moves the record material from reading position to printing position and return, and obviously said printing impression mechanism moves in unison with said framework. Therefore, when the machine is at rest, the impression platen is in a non-printing or substantially vertical position, as shown in Fig. 2, and during the machine operation said platen is moved from non-printing position to a printing position, as shown in Fig. 3, and the impression mechanism is simultaneously engaged with its operating mechanism, which upon operation causes the platen to squeeze the record material and the inking ribbon into contact with the type wheels 319 to record the data relating to the machine operation being performed.

The impression mechanism comprises right-hand and lefthand arms 805 and 806 (Figs. 2, 3 and 6) similar in outline and each having similar slots 807 which engage the trunnions 741 carried by each of the plates 743 and 744. Similar slots 808 in the lower ends of each of the arms 805 and 806 and parallel to the slots 807, engage studs

809 carried by the plates 743 and 744, to slidably mount said arms 805 and 806 in the record material framework. Each of the arms 805 and 806 has on the upper end thereof inturned ears, which straddle similar ears on a U-shaped platen support bar 811, each set of ears being pivotally connected to each other by means of pins 810 which pass through borings therein. The channel formed in the U-shaped bar 811 (Figs. 2 and 6) 5 supports a long resilient impression block 812, which is secured against displacement by three screws threaded into the side of the channel bar, said screws having pointed ends which penetrate the resilient platen block 812. The bottom of the 10 platen block 812 rests on a long adjusting plate (not shown) supported in the channel of the bar 811, said plate being adjustable by means of screws threaded into the bottom of the frame, to 15 in turn adjust the face of the platen block 812 in relation to the type wheels 319. 20

20 When the framework which supports the record material is rocked from reading position, as shown in Fig. 2, to printing position as shown in Fig. 3, the platen block 812 and its supporting framework also move in unison therewith and the line-spacing mechanism functions in a manner to be presently described to cause the record material to be automatically line-spaced prior to operation of the impression mechanism.

25

30 Mechanism for rocking the rocking material framework from non-printing position to print-

ing position and vice versa, comprises two identical studs 813 (Figs. 3 and 6) carried by the plates 743 and 744, said studs adapted to be engaged with notches in the upper ends of similar arms 814 when the printer framework 726 and 727 is properly mounted in the machine, as shown in Fig. 2. The lower ends of the arms 814 are slotted to embrace a shaft 488 journaled in the frames 40 60 and 61, and each of said arms carries a stud 815, which extends through corresponding slots in each of two arms 816 secured to the shaft 488. A compressible spring 817 forms a resilient connection between the pair of arms 814 and 816 and 45 constantly urges said arms 814 upwardly to maintain the notches therein in engagement with the studs 813 (Figs. 2 and 3) regardless of the angular relationship of said studs to the shaft 488.

Secured to the shaft 488 (Fig. 3) is a crank 489 having pivoted thereto a pitman 490 carrying a roller 491 (Fig. 4) cooperating with a cam groove 492 in a cam 493, which is secured to the main drive shaft 130. This cam groove 492, through the pitman and crank, rocks the shaft 488 first clockwise and return.

Initial movement counterclockwise of the shaft 488 (Figs. 2 and 3) rocks the record material framework 743 and 744 from the position shown in Fig. 2 to the position shown in Fig. 3, to bodily

60 move the record material supply roll 742, the receiving roll 731, and the impression platen 812 from reading position to printing position. As the impression platen 812 and its assembly move to printing position, the cam slots 752 (Figs. 2, 45 and 2), in cooperation with the rollers 152, rock

65 and 39, in cooperation with the rollers 153, rock the levers 754 clockwise in relation to the record material framework, which is also moving in a clockwise direction at this time. Clockwise movement of the levers 754 through the stud 185 carried by the righthand lever 754 (Fig. 6) imparts a similar movement to the lever 784 (Fig. 8) which by means of the stud 183, in cooperation with the slot 182 shifts the link 781 forwardly to rock the disk 173 (see also Fig. 11) also in a clockwise direction. Clockwise movement of the disk

773 (Figs. 8 and 11) causes the feed pawl 771 carried thereby, in cooperation with the teeth of the ratchet 770, to rotate the core 760 (Fig. 10) and the record material receiving roll 761 the equivalent of one tooth space to line-space the record material prior to operation of the impression mechanism.

Clockwise movement of the levers 754 (Figs. 2 and 6) through the connections comprising the rod 755, the links 756, the arms 757 and 758, and the guide rod 759 slightly and momentarily collapses a portion of the record material guiding means to relieve the tension on the web of the record material while it is being line-spaced, to overcome the danger of tearing said web and to prevent unnecessary strain on the line-spacing mechanism.

Clockwise movement of the record material framework 743 and 744 from reading position to printing position (Figs. 2, 3 and 6) engages two axially alined studs 818, carried by each of the impression arms 805 and 806, with notches in the upper ends of operating arms 820 and 821 secured to the shaft 734. An extension of the arm 820 has pivotally connected thereto the lower end of a toggle link 822, the upper end of which is pivotally connected by a stud 823 to a companion toggle link 824 pivotally mounted on a stationary stud 825 in the right side frame 61. The stud 823 also pivotally supports the forward end of an operating pitman 826, the rear end of which is bifurcated to straddle the shaft 130, said pitman carrying a roller 827 which cooperates with a camming groove 828 in the righthand face of the cam 301. The cam groove 828, in cooperation with the roller 827, shifts the pitman 826 first forwardly (to the left as viewed in Fig. 3) and then back to normal position, after the type wheels 319 have been set by the differential mechanisms shown and described in the parent application. Forward movement of the pitman 826, which occurs after the record material framework has been rocked to printing position, as shown in Fig. 3, expands or lengthens the toggle links 822 and 824 to rock the arm 820, the shaft 734, and the arm 821 clockwise. Clockwise movement of the arms 820 and 821 shifts the impression arms 805 and 806 rearwardly (to the right as viewed in Fig. 3) on their supporting studs 747 and 809 to cause the impression platen 812 to press the web of record material and an inking ribbon 829 into contact with all of the type wheels to record the transaction on the web of record material as shown in Fig. 5.

After the impression has been made the pitman 826 is returned rearwardly (to the right as viewed in Fig. 3) to shift the impression assembly to normal position, after which the shaft 488 is returned clockwise by the cam groove 492 (Fig. 4) to restore the record material framework 743 and 744 to reading position. When the framework is in reading position, the position of the record material carrying the recordings of the last transaction and several previous transactions is visible through an opening 830 (Fig. 1) in a closure 831 hinged to the cabinet 69. The closure 831 encloses the record material framework 726 and 727 and the opening 830 is preferably covered with a transparent plastic material 832. An opening 833 (Fig. 1) in the transparent material 832 exposes the lefthand edge of the record material so that various data may be autographed thereon opposite the printed records of the transactions, if desired. A table 834 (Figs. 6 and 8) supported by the rods 745 and 75

755 of the record material framework, is located directly beneath the autographic opening 833 and provides a backing for the web of the record material for the autographic entering of items thereon.

When the printer framework 726 and 727 is removed from the machine it is necessary to latch the record material framework 743 and 744 in reading position, as shown in Figs. 1 and 6, so that the studs 813 will remain in alinement with the notches in the upper ends of the arms 814 so that said studs will reengage said notches when the record material framework is again placed in the machine.

This retaining of the rockable portion of the record material framework in reading position, as shown in Fig. 2, is effected by two identical latches 835 (Figs. 1 and 6) pivoted on studs 836 carried by the plates 726 and 727. The latches 835 are urged clockwise by the springs 737 which are tensioned between said latches 835 and the latches 735, which latter latches secure the printer framework in operating position, as previously explained. Each of the latches 835 has a stud 837, which studs extend through corresponding clearance openings in the plates 726 and 727 and cooperate with corresponding camming surfaces 838 on each of the plates 730 and 731 to retain the hook-shaped upper ends of said latches 835 disengaged from the rollers 753, which it will be remembered are carried by the levers 754, so that the record material framework 743 and 744 may be rocked to and from printing position during the machine operation.

When the printer framework, including the plates 726 and 727, and all the parts assembled therebetween, is removed from the machine by manual release of the latches 735 in the manner previously explained, withdrawal of the studs 837 from the surfaces 838 permits the springs 737 to rock the latches 835 clockwise, as viewed in Fig. 1, into engagement with the rollers 753 to secure the levers 754 and the rockable record material framework in reading position, as shown in Fig. 2, so that the studs 813 will reengage the notches in the upper ends of the arms 814 when the printer framework is again placed in the machine.

As brought out in the general description of the impression mechanism, the printer framework is accessible through the closure 831, which is hinged to the cabinet 69, and said closure is locked in closed position when the machine is being used as a cash register or when the machine is completely locked against operation, and is unlocked when the machine is set for either read, reset or add operation, as has been fully explained in the parent application.

The closure 831 has two downward extensions 841 (one of which is shown in Fig. 1) each carrying a stud 842 adapted to be engaged by the hook-shaped ends of two identical latches 843 pivoted on studs 844 carried, respectively, by the frames 61 and 60, to normally lock said closure 831 closed. Springs 845, tensioned between studs 846 in the latches 843, and stationary studs 847 in each of the frames 60 and 61, urge said latches 843 clockwise into engagement with the studs 842. An extending tip on each of the latches 843 cooperates with the studs 847 to limit the clockwise movement of the latches 843, under the influence of the springs 845, in relation to the studs 842, so that said studs may properly by-pass the rounded noses of the latches 843 when the closure 831 is being closed.

The studs 848 cooperate with upwardly extending fingers of two latch operating levers 848 pivoted on studs 849 in the frames 61 and 60. Each of the downward extensions of the levers 848 has an arcuate surface 850 adapted to cooperate with camming nodes 851 on two identical cams 852 secured on the shaft 459. When the machine is in the locked position so that it cannot be operated, and also when it is in the position to be operated as a cash register the cam 852 is in the position shown in Fig. 1. However, when the machine is in a position to take a reading operation, a reset operation, or in a position to be operated as an adding machine, the shaft 459 is turned and the same nodes 851, by their cooperation with the cam surfaces 850, rock the levers 848 clockwise, whereupon the latches 843 are rocked counter-clockwise and disengaged from the studs 842 to release the closure 831 so that it may be opened by the operator to gain access to the printing mechanism.

A tension device is provided for applying frictional drag to the record material supply roll 742 (Figs. 6 and 8), to insure that the web of the record material is held taut when the record material framework 743 and 744 is in either reading position or printing position, as shown, respectively, in Figs. 2 and 3.

The tension device includes a friction plate 853 (Figs. 6 and 8), having bent-over ears which freely engage the shaft 746, this plate having a slot 854 through which extends a pin 855, free in a hole in said shaft 746. A torsion spring 856 loosely coiled around the shaft 746 has one end thereof looped around an annular groove in one end of the pin 855 to retain said pin in place and the other end of said spring is looped around the downward edge of the plate 853. The spring 856 is tensioned to urge the plate 853 counter-clockwise, as viewed in Fig. 8, into frictional engagement with the circumference of the supply roll 742 to impart a braking effect to said supply roll to insure that the web of the record material is retained taut when the record material framework is in reading position or printing position.

The pin 855, in cooperation with the slot 854, prevents lateral displacement of the friction plate 853 on the shaft 746 and determines the extent of rotary movement of said plate under the influence of the spring 856.

While the form of mechanism herein shown and described is admirably adapted to fulfill the objects primarily stated, it is to be understood that it is not intended to confine the invention to the one form or embodiment herein disclosed, for it is susceptible of embodiment in various forms, all coming within the scope of the claims which follow.

What is claimed is:

1. In a machine of the character described, adapted to print records on record material, and having type carriers, the combination of a framework adapted to be readily removed from or installed in said machine; a record material supply roll; a record material receiving roll; means to guide the web of the record material from the supply roll to the receiving roll; means to rotate the receiving roll to feed the web of the record material; friction means cooperating with the supply roll to retain the web of the record material taut; an impression member to impress the web of the record material against the type carriers to print records; a rockable framework supported in the removable framework, said rockable framework adapted to support the supply

roll, the receiving roll, the guide means, the receiving roll rotating means, and the impression means; means to rock the rockable framework to move all of the parts carried thereby, including the impression member, from normal position to working position and return, to move the web of the record material from reading position to printing position and return; means, effective when the rockable framework is being moved from normal position to working position, to momentarily retract a portion of the record material guiding means to release the tension on the web of the record material, while said record material is being moved from reading position to printing position; and means whereby the retracting means operates the receiving roll rotating means, while the tension is released on the record material.

2. In a machine of the character described, adapted to print records on record material, and having type carriers, the combination of means to press the record material against the type carriers; a record material supply roll; a record material receiving roll; means to advance the receiving roll to line-space the record material; means to guide the record material from the supply roll, between the pressing means and the type carriers, and onto the receiving roll; a common pivoted support for the pressing means, the supply roll, the receiving roll, the receiving roll advancing means, and the guide means; means to rock said common pivoted support and all the parts carried thereby, including the pressing means, as a unit from a normal position to a working position and return, to move the record material from a reading position to a printing position and return; and a movable framework for detachably supporting said rockable framework and the parts carried thereby as a unit, in the machine, so that the complete record material mechanism may be readily installed in or removed from said machine as a unit, without disturbing other mechanism on the machine.

3. In a machine of the character described, adapted to print records on record material, and having type carriers, the combination of means to press the record material against the type carriers; a record material supply roll; a record material receiving roll; means to advance the receiving roll, to feed the record material; means to guide the record material from the supply roll, between the pressing means and the type carriers, and onto the receiving roll; means to operate the pressing means to print records on the record material; a common pivoted support for the pressing means, the supply roll, the receiving roll, the receiving roll, the advancing means, and the guide means; means to rock said common pivoted support and all the parts carried thereby, including the pressing means, as a unit from a normal position to a working position and return, to move the record material from a reading position to a printing position and return; and a movable framework for detachably supporting said rockable framework and the parts carried thereby, as a unit in the machine so that the complete record material mechanism may be readily installed in or removed from said machine without disturbing other mechanism thereof.

4. In a machine of the character described, having type carriers adapted to print records on record material, the combination of means to impress the record material against the type carriers; means to operate the impressing means; a record material supply roll; a record material

receiving roll; means to advance the receiving roll to line-space the record material; means to guide the record material from the supply roll, between the impressing means and the type carriers, and onto the receiving roll; a common pivoted support for the impressing means, the supply roll, the receiving roll, the advancing means, and the guide means; means to rock said common pivoted support and all the parts carried thereby, including the impressing means, as a unit from a normal position to a working position and return, to move the record material from a reading position to a printing position and return, and to connect the impressing means to its operating means; and a movable framework for demountably supporting said rockable framework and the parts carried thereby as a unit in the machine, so that the complete record material mechanism may be readily installed in and removed from said machine without disturbing other mechanism thereof.

5. In a machine of the character described, having type carriers adapted to print records on record material, the combination of a framework adapted to be easily and conveniently removed from or installed in the machine as a unit; means to impress the record material against the type carriers to print records; a record material supply roll; a record material receiving roll; means to guide the record material from the supply roll, between the impressing means and the type carriers, and onto the receiving roll; tension means cooperating with the supply roll to hold the web of the record material taut; a framework rockably mounted in the first-named framework, said second framework adapted to support the record material supply and receiving rolls, the impressing means, and the record material guiding means; means to rock the second framework to move said framework and all the parts carried thereby, from a normal position to a working position and return, to move the record material and its guide means from reading position to printing position and return without sliding the web of the record material over stationary guides and supports; means supported by the second framework and actuated by cam openings in the first framework, when said second framework is rocked from normal position to working position, to retract a portion of the guiding means to momentarily release the tension on the record material; and means actuated by the retracting means to rotate the receiving roll to line-space the record material at the time the tension is released thereon.

6. In a machine of the class described, having type carriers adapted to print records on record material, the combination of means to impress the record material against the type carriers to print records; a record material supply roll; a record material receiving roll; means to guide the web of the record material from the supply roll, between the impressing means and the type carriers, and onto the receiving roll; means to rotate the receiving roll to line-space the record material; tension means to hold the web of the record material taut; a rockable framework adapted to support the impressing means, the supply roll, the receiving roll, the record material guiding means, and the receiving roll rotatable means, said framework removably mounted in the machine so that the entire record material assembly may be readily removed from or installed in said machine, without interfering with or disturbing other mechanisms of the machine;

means to rock the framework and all the parts carried thereby from a normal position to a working position and return, to bodily move the record material supply and receiving rolls, the web of said record material, and the guiding means therefor from a reading position to a printing position and return, without sliding said web over stationary guides and supports; and means to move a portion of the guiding means relatively to the framework, as said framework is being rocked to printing position, to momentarily release the tension on the web of the record material, said moving means also adapted to actuate the receiving roll rotating means to line-space the record material while the tension is released thereon.

7. In a readily installable and removable record material unit for cash registers in which the record material is adapted to be moved from a reading position to a printing position and return, said cash registers having type carriers, the combination of means to impress the record material against the type carriers; means to operate the impressing means; a record material supply roll; a record material receiving roll; means, including a movable rod, to guide the record material from the supply roll, between the impressing means and the type carriers, and onto the receiving roll; means to rotate the receiving roll; means to rotate the receiving roll to line-space the record material; tension means to normally hold the web of the record material taut; a rockable framework removably mounted in the cash register and adapted to support the impressing means, the supply roll, the receiving roll, the record material guiding means, and the receiving roll rotating means; arms pivotally mounted on the framework, said arms adapted to support the movable guide rod; means to rock the framework and all the parts carried thereby, from a normal position to a working position and return, to connect the impressing means to and disconnect it from its operating means and to move the supply roll, the receiving roll, the web of the record material, and the guide means from reading position to printing position and return, without sliding said web over stationary guides and supports; and means effective when the framework is rocked, to move the arms and the movable guide rod supported thereby relatively to said framework, to momentarily release the tension on the record material, said moving means also adapted to simultaneously actuate the receiving roll rotating means to line-space the record material while the tension thereon is released.

8. A readily installable and removable record material unit for cash registers in which the record material is adapted to be moved from a reading position to a printing position and return, said cash registers having a plurality of type carriers, comprising in combination a rockable framework removably mounted in the cash register; means, mounted in the rockable framework, to impress the record material against the type carriers to print records thereon; means to operate the impressing means; a record material supply roll; a record material receiving roll, both of said rolls mounted in the rockable framework; a plurality of rods to guide the record material from the supply roll, between the impressing means and the type carriers, and onto the receiving roll, said rods being mounted in the rockable framework; means to rotate the receiving roll to line-space the record material; tension means cooperating with the supply roll to nor-

mainly maintain the web of the record material taut; means to rock the framework and all the parts carried thereby, from a normal position to a working position and return, to connect the impressing means to and disconnect it from its operating means and to move the entire record material mechanism, including the supply roll, the receiving roll, and the guide rods, from a reading position to a printing position and return, without sliding the web of the record material over stationary guides and supports; and means, actuated by the rocking of the framework, to move one of the guide rods relatively to said framework to momentarily release the tension on the web of the record material, said moving means also adapted to simultaneously actuate the receiving roll rotating means, to feed the record material while the tension thereon is released.

9. In a machine of the character described, having a plurality of type carriers for printing records on record material, the combination of means to impress the record material against the type carriers to print records thereon; means to operate the impressing means; a record material supply roll; a record material receiving roll; means to rotate the receiving roll to feed the web of the record material; tension means cooperating with the supply roll to normally maintain the web of the record material taut; a plurality of rods to guide the web of the record material from the supply roll, between the impressing means and the type carriers, and onto the receiving roll; a rockable framework adapted to support the impressing means, the supply roll, the receiving roll, and the guide rods; means to rock the framework and all the parts carried thereby, from a normal position to a working position and return, to connect the impressing means to and disconnect it from its operating means and to move the entire record material mechanism, including the supply roll, the receiving roll, and the guide rods, from a reading position to a printing position and return, without sliding the web of the record material over stationary guides and supports; a demountable framework for removably supporting the rockable framework in the machine, so that the entire record material assembly may be readily and easily removed from the machine without the use of tools and without disturbing other mechanism of the machine; cam slots in the demountable framework; and means cooperating with the cam slots and effective when the rockable framework is moved from normal position to working position, to move one of the guide rods relatively to said framework to release the tension on the web of the record material, said moving means also adapted to simultaneously actuate the receiving roll rotating means to feed the record material while the tension is released thereon.

10. In a readily installable and removable record material unit for a machine of the class described, in which machine the record material is adapted to be moved from a reading position to a printing position and return, said machine having type carriers, the combination of a framework removably mounted in the machine and adapted to be readily removed or installed without the use of tools and without disturbing other mechanism of the machine; a record material supply roll; a record material receiving roll; means to impress the web of the record material against the type carriers to print records thereon; means, including a rod, to guide

the web of the record material from the supply roll, between the impressing means and the type carriers, and onto the receiving roll; means to rotate the receiving roll to feed the web of the record material; tension means cooperating with the supply roll to normally maintain the web of the record material taut; a second framework rockably mounted in the removable and installable framework and adapted to support the supply roll, the receiving roll, the impressing means, and the guiding means; means to rock the rockable framework and all the parts carried thereby, from a normal position to a working position to connect the impressing means to its operating means and to move the record material from reading position to printing position, without sliding the web of said record material over stationary guides and supports; arms pivoted to the rockable framework and adapted to support the guide rod; cam slots in the removable framework; rollers on the arms cooperating with the cam slots, as the rockable framework is moved from normal position to working position, to move the guide rod relatively to said framework to release the tension on the web of the record material; and connections between one of the arms and the record material receiving roll rotating means, to actuate said rotating means to feed the record material while the tension thereon is released.

11. In a readily installable and removable record material unit for a machine of the class described, in which machine the record material is adapted to be moved from a reading position to a printing position and return, said machine having type carriers, the combination of a framework adapted to be readily installed in or removed from said machine without the use of tools and without disturbing other mechanisms of the machine; a record material supply roll; a record material receiving roll; means to impress the web of the record material against the type carriers to print records; means to rotate the record material receiving roll to line-space the record material; means to guide the web of the record material from the supply roll, between the impressing means and the type carriers, and onto the receiving roll; tension means cooperating with the supply roll to normally maintain the web of the record material taut; another framework, comprising two portions, rockably mounted in the installable and removable framework and adapted to support the supply roll, the receiving roll, the impressing means, and the guide means; means to rock the rockable framework and all the parts carried thereby, from a normal position to a working position, to connect the impressing means to its operating means and to move the record material from reading position to printing position without sliding the web of said record material over stationary guides and supports; means to move one portion of the rockable framework in relation to the other portion of said framework, as said framework is being moved from normal position to working position, to retract a portion of the guiding means to momentarily release the tension on the web of the record material; and connections between the moving means and the receiving roll rotating means to actuate said rotating means to line-space the record material while the tension thereon is released.

12. A readily installable and removable record material unit for a machine of the class described, in which machine the record mate-

rial is adapted to be moved from a reading position to a printing position and return, said machine having type carriers, said record material unit comprising in combination a demountable framework supported in the machine and adapted to be readily installed in or removed from said machine without the use of tools and without disturbing other mechanisms of the machine; a rockable framework mounted in the demountable framework; means supported by the rockable framework to impress the record material against the type carriers to print records; means to operate the impressing means; a record material supply roll rotatably mounted in the rockable framework; a first set of arms pivoted to the rockable framework; a record material receiving roll rotatably supported by the first set of arms; means to rotate the receiving roll, to line-space the record material; tension means cooperating with the supply roll to normally maintain the web of the record material taut; a second set of arms pivoted to the rockable framework; links connecting the two sets of arms; guide means, including a rod supported by each set of arms, to guide the web of the record material from the supply roll, between the impressing means and the type carriers, and onto the receiving roll; means to rock the rockable framework and all the parts carried thereby, from a normal position to a working position, to connect the impressing means to its operating means and to move the record material from reading position to printing position, without sliding the web of said record material over stationary guides and supports; means coacting with the second set of arms and effective when the rockable framework is moved from normal position to working position, to move the two sets of arms and the rods carried thereby relatively to said framework, to momentarily release the tension on the web of the record material; and connections between the second set of arms and the receiving roll rotating means whereby the moving means actuates said rotating means, to cause the web of the record material to be line-spaced while the tension is released thereon.

13. A readily removable record material unit for a machine of the class described, having type carriers and in which machine the record material is movable from a reading position to a printing position and return, said record material unit comprising, in combination, a framework demountably supported in the machine and adapted to be readily removed or installed without the use of tools and without disturbing other mechanism of the machine; a rockable framework mounted in the demountable framework; means, supported by the rockable framework, to impress the record material against the type carriers to print records; means to operate the impressing means; a record material supply roll rotatably mounted in the rockable framework; a first set of arms pivoted to the rockable framework; a record material receiving roll rotatably supported by the first set of arms; means to rotate the receiving roll, to line-space the record material; tension means cooperating with the supply roll to normally maintain the web of the record material taut; a second set of arms pivoted to the rockable framework; links connecting the two sets of arms; guide means, including a rod supported by each set of arms, to guide the web of the record material from the supply roll, between the impressing means

and the type carriers, and onto the receiving roll; means to rock the rockable framework and all the parts carried thereby, from a normal position to a working position, to connect the impressing means to its operating means and to move the record material from reading position to printing position, without sliding the web of said record material over stationary guides and supports; cam slots in the demountable framework; rollers on the second set of arms cooperating with the cam slots, to move the two sets of arms and the rods carried thereby relatively to the rockable framework, when said framework is moved from normal position to working position, to momentarily release the tension on the web of the record material; and connections between the second set of arms and the receiving roll rotating means, whereby relative movement of said arms actuates said rotating means to cause the web of the record material to be line-spaced while the tension is released thereon.

14. In a readily installable and removable record material unit for a machine of the class described, the combination of a rockable framework removably mounted in the machine; a record material supply roll mounted in the rockable framework; a record material receiving roll mounted in the rockable framework; a plurality of rods mounted in the rockable framework, said rods effective to guide the record material from the supply roll onto the receiving roll; means to rotate the receiving roll to feed the record material; means to rock the rockable framework and all the parts carried thereby, including the supply roll, the receiving roll, and the guide rods, from a normal position to a working position and return without sliding the web of the record material over stationary guides and supports; and means, actuated by the rocking of the rockable framework, to momentarily retract certain of the guide rods to slacken the web of the record material, said retracting means also effective to simultaneously actuate the receiving roll rotating means to feed the record material while the web thereof is in a slackened condition.

15. In a readily installable and removable record material unit for a machine of the class described, in which machine the record material is adapted to be moved from a reading position to a printing position and return, said record material unit comprising in combination a demountable framework constructed and arranged to be readily installed in or removed from the machine; a rockable framework mounted in the demountable framework; a record material supply roll mounted in the rockable framework; a first set of arms pivoted to the rockable framework; a record material receiving roll rotatably supported by the first set of arms; means to rotate the receiving roll to feed the record material; a second set of arms pivoted to the rockable framework; links to connect the two sets of arms; guide means, including a rod supported by each set of arms, to guide the web of the record material from the supply roll onto the receiving roll; means to rock the rockable framework and all the parts carried thereby from reading position to printing position to eliminate the sliding of the web of the record material over stationary guides and supports; means coacting with the second set of arms and effective while the rockable framework is being rocked from reading position to printing position, to move the two sets of arms and the rods carried thereby relatively to said framework to momentarily re-

19

tract said rods from the web of the record material to introduce slack into said web; and means to actuate the receiving roll rotating means during rocking of the rockable framework, to feed the record material while the web thereof is in a slackened condition.

16. In a record material unit for a machine of the class described, in which the record material is arranged to be moved from a reading position to a printing position and return, said record material unit comprising in combination a first framework constructed and arranged to be easily and conveniently removed from or installed in the machine; a second framework rockably supported by the first framework; a record material supply roll mounted in the second framework; a record material receiving roll mounted in the second framework; means mounted in the second framework to guide the record material from the supply roll onto the receiving roll; means to rock the second framework from reading position to printing position and return, to move the record material from reading position to printing position and return without sliding the

20

web of said record material over stationary guides and supports; means supported by the second framework and actuated by the first framework, when said second framework is rocked from reading position to printing position, to momentarily retract a portion of the record material guiding means to momentarily slacken the web of the record material; and means to rotate the receiving roll, while the web of the record material is slackened, to feed said record material.

MARY KLOSTERMAN,
*Executrix of the Estate of Joseph J. Klosterman,
Deceased.*
